ATTACHMENT FOR INCANDESCENT-LAMP SOCKETS.

1,135,207.

Specification of Letters Patent. Patented Apr. 13, 1915.

Application filed February 8, 1913. Serial No. 746,995.

To all whom it may concern:

Be it known that we, JOSEPH SACHS and CHARLES A. FRANCIS, citizens of the United States, residing at Hartford, in the county 5 of Hartford and State of Connecticut, have invented certain new and useful Improvements in Attachments for Incandescent-Lamp Sockets, of which the following is a specification.

10 This invention relates to attachments for incandescent-lamp sockets among the principal objects of the invention being the provision of an article of this character which is simple in construction and which can be 15 quickly applied to and as readily removed from a socket but which when in position thereon will be held against accidental dislodgment in a positive and certain manner.

The invention possesses other features of 20 novelty and advantage which with the foregoing will be stated at length in the following description wherein we will set forth in detail that form of embodiment of the invention which we have selected for illustration in the drawings accompanying and forming part of the present specification to enable those skilled in the art to practise the invention. We can depart from this showing in several particulars within the scope 25 30 of the invention defined by the claims following said description.

Referring to said drawings: Figure 1 is a front elevation of an attachment involving our invention. Figs. 2 and 3 are respectively a side elevation and top plan view of the same, and, Fig. 4 is a transverse section on the line 4—4 of Fig. 3, showing the socket omitted from the other figures.

Like characters refer to like parts 40 throughout the several views.

Our invention can be incorporated in widely-different kinds of devices being represented as embodied in a reflector in which connection it is of particular utility; it can 45 be employed with equal advantage in many other connections, for example in a guard for incandescent lamps.

The body of the device illustrated consists of a reflector member 2, being approximately of semi-ovovate or half pear form, although this particular shape is not always necessary, and generally but not necessarily, 50 consists of a sheet-metal shell. In the main

said body is like that found in the so-called "half reflector."

Extending outward from the reflector member or body portion 2 is a neck 3 and although the two parts are preferably integral this is not always necessary. The neck as shown presents a clamp or clip being adapted to yieldingly embrace the socket 4 of an incandescent lamp and while this yielding relation can be obtained in several ways, the best results are secured by making said neck or clip resilient. As shown the 60 65 70 75 80 85 said neck or clip is of substantially circular form being preferably but not essentially a little more than half a circle but less than a full circle in extent. The interior diameter of the said clip is slightly less than the external diameter of the socket so that the clip will tightly hug said socket. Owing to the construction of the said neck or clip in the manner described, there is formed therein the lateral mouth or slot 5 from which it will be clear that said clip is applied to and removed from the socket by a relative lateral motion. While there may be cases where the grip of the clip upon the socket due merely to friction supplemented by the 90 95 resilience of said neck is sufficient to hold the attachment in place we prefer in all cases not to rely upon this but to provide in addition thereto, a positive holding means which will position the attachment in definite relation longitudinally of the attachment and such means may vary radically. For this purpose we have furnished an interlock between the two parts; consisting for example of a channel in one to receive a bead on the other, the socket 4 as illustrated having such a bead as 6 and the neck 3 having an internal channel or groove as 7 to receive said bead.

In applying the article the neck 3 is 95 placed against the socket 4 with the latter partly in the mouth 5 and the parts are relatively laterally moved toward each other which has the effect of opening the neck or clip 3 to its maximum extent at which point 100 the socket will be practically wholly within the clip and after which said clip will snap instantly in place, the groove 7 receiving the bead 6.

It should be observed that the neck or 105 clip 3 abruptly joins the reflector body 2

and that the sides of the open portion thereof diverge away from said neck by reason of which said reflector body will interfere in no wise with the lamp. It should 5 also be noted that the groove or channel 7 is located between the outer end of said clip and where the latter joins the body 2. To facilitate opening of the clip 3 when it is desired to place the attachment, said clip 10 may be provided near its front open side thereof with finger pieces 8.

To increase the hold of the clip or neck 3 upon the socket 4, the former may as 15 shown, be provided along the exterior of its outer edge, with a bead 9, and this bead may be further strengthened by an inclosed wire 10 or other means.

It will be understood that the length of 20 the body portion or reflector member 2 exceeds the length of the lamp or of the exposed surface thereof when in the socket so that said body portion does not necessarily have to come into contact with said lamp; certainly it does not require to do so so far 25 as its being secured in place is concerned, it being through its said neck, connected with the socket by reason of which said body cannot injure the lamp. Owing to the fact that the said neck or clip 3 has an 30 internal channel or groove as set forth, we adapt the device for interlocking connection with standard sockets which at the present time are generally provided with an external bead.

35. What we claim is:

1. An attachment for incandescent-lamp sockets comprising a body provided with an integral resilient neck having a lateral mouth to adapt said neck to be laterally

applied to and removed from a socket, said neck having integral means for positively interlocking the same with said socket and said neck and interlocking means constituting the only means for holding the attachment in operative relation with said socket. 15

2. An attachment for incandescent-lamp sockets comprising a body provided with an integral resilient neck having a lateral mouth to adapt said neck to be laterally applied to and removed from a socket, said neck having between its ends an interior channel extending approximately uninterruptedly from side to side thereof to interlock with the bead of a socket, and the neck and the wall of the channel constituting the 50 only means for holding the attachment in operative relation with said socket. 55

3. An attachment for incandescent lamp sockets comprising a body provided with a resilient neck having a lateral mouth to 60 adapt said neck to be laterally applied to and removed from a socket, said neck having between its ends integral means for positively interlocking the same with said socket, the body being shaped to be free of 65 the bulb of the lamp to the socket of which said neck is connected and the said neck and interlocking means constituting the only means for holding the attachment in operative relation with the socket. 70

In testimony whereof we affix our signatures in presence of two witnesses:

JOSEPH SACHS.
CHARLES A. FRANCIS.
